UNITED STATES PATENT OFFICE.

RICHARD M. FOSTER, OF WORCESTER, MASSACHUSETTS, ASSIGNOR TO BREWER & COMPANY, INC., OF WORCESTER, MASSACHUSETTS, A CORPORATION OF MASSACHUSETTS.

TENSION DEVICE FOR CIRCULAR-KNITTING MACHINES FOR MAKING SEAMLESS ELASTIC STOCKINGS AND THE LIKE.

Application filed August 30, 1922. Serial No. 585,294.

To all whom it may concern:

Be it known that I, RICHARD M. FOSTER, a citizen of the United States, residing at Worcester, in the county of Worcester and 5 State of Massachusetts, have invented a new and useful Tension Device for Circular-Knitting Machines for Making Seamless Elastic Stockings and the like, of which the following is a specification.

10 This invention relates to a tension device for tensioning and stretching the elastic thread employed in knitting seamless elastic goods of tubular shape, and the particular object thereof is to provide a tension device 15 which can be varied with fine gradations by hand so as to provide for tapering the hose gradually instead of by a series of steps as has been customary heretofore, thus greatly improving the appearance and increasing 20 the value of the product.

The invention also involves the provision of a circular knitting machine for this purpose with a stationary table on which runs a roller propelled around with the rotating 25 knitting cams and capable of being moved toward or from the center to increase or decrease the tension that is controlled by it, and improvements in the way of mounting and operating the tension roller as well as 30 the support for the elastic thread and the details of the adjusting device.

Reference is to be had to the accompanying drawings, in which—

Fig. 1 is a plan of a circular knitting machine provided with a preferred embodiment 35 of the present improvements;

Fig. 2 is a side view of the same;

Fig. 3 is a sectional view on the line 3—3 of Fig. 1, showing the means for rotating 40 the tension device; Fig. 4 is an enlarged plan of the cam ring and associated parts; and

Fig. 5 is an enlarged plan of the slide.

It is well known that in the manufacture of elastic knitted hosiery on circular knitting machines, the elastic thread is laid into the work and held therein by the knitted loops formed from the knitted threads. If the elastic thread is fed to the needles without tension so that the length of the thread 45 is equal to the circumference of the circle of needles, the tube produced is substantially the diameter of the needle cylinder. In order to reduce the diameter and vary it for shaping the product to the shape of the leg

on which it is to be worn, it has been customary to stretch the elastic thread as it is laid or knitted into the course. Then when the stretched knitted tube has left the needles on which it is produced, the elastic thread contracts and reduces the diameter 55 of the tube, the reduction depending upon the amount of stretch. I adopt this method of shaping the hose. Heretofore it has been customary to provide the operator of the machine with a card giving instructions as 60 how to adjust the tension. These adjustments necessarily were made by sudden changes in the tension. This resulted in weaving a fabric that produced a tube of cylindrical form for a few courses and then 65 suddenly changed to one of larger or smaller diameter. The hosiery produced, therefore, as is shown in the finished state, is provided with a series of readily distinguishable ribs 70 or zones of different diameter, all of them 75 cylindrical.

It is the object of the present invention to provide an arrangement whereby these cylindrical parts can be done away with and the hose made in a conical form or shape, as 80 desired, without any sudden changes that can be observed by the buyer. This not only provides a much more attractive article for sale but one that is more comfortable to wear as there will be no elastic threads that 85 have to be stretched materially more than the adjacent ones when it is worn.

I do not make any changes in the present knitting machine and I have shown one of well known type. Of course it will be understood that the invention can be applied to other types of circular knitting machines. In the knitting machine shown, there is the usual supporting frame 10. The machine is driven by a belt 11 operating on a pulley 12 90 on a shaft 13 which by gearing 14 rotates a shaft 15 on which is located a bevel gear 16. The fixed knitting cylinder 17, fixed rubber dial 18 and rotating knitting cam support 19 having a flange 19^a are used as usual. This support 19 is carried above a bevel gear 20 95 positively rotated by the gear 16 meshing with it. A handle 21 is mounted on the shaft 13 for rotating the knitting cams by hand for adjustment and threading or the like.

I provide the frame 10 with a circular table 22 in horizontal position. This table

- is provided with a central perforation 23 for the needle cylinder 17 and connected parts. In this opening there is a circular plate 24 which is fixed on the gear 20 and is provided with a dog 25 projecting up above the table 22. This dog is located circumferentially between the ends of the split circular flange 19^a which constitutes or supports the knitting cams. It extends up between the two ends of this member and being positively driven drives these cams and therefore the knitting elements of the machine.
- Fixed on this flange 19^a at the opposite sides are two parallel brackets 26 which carry a cross bracket 27 on which are supported the shafts of two tension feeding rollers 28 and 29. These rollers are geared together to rotate positively by gears 30. The roll 28 rests by gravity on the roll 29 below and they feed in the elastic thread E. From what has been said, it will be observed that the whole frame composed of the parts 26 and 27 must rotate with the rotating knitting cams.
- On the bracket 26 is mounted an arm 60 carrying a can 61 having deposited therein the elastic thread E and this is drawn out over a guide 62 to an eye 63 and from that it passes between the rolls 28 and 29 to the knitting cylinder 17.
- On the shaft 31 on which is located the bottom roll 29 is pivoted a bracket 32. This bracket has projecting from it and rigidly secured to it a pair of parallel bars 33 and 34, one of which is provided with a scale. The ends of these bars are connected together by a plate 35 and these four parts constitute a rectangular frame rigidly connected with the pivoted bracket 32.
- On this frame is a central shaft 36 mounted to rotate in bearings at the ends of the frame. This is shown in the form of a square shaft having teeth 37 thereon constituting a ratchet. Slidingly mounted on this shaft is a hub 38 having a square opening for receiving the shaft and therefore rotating positively with the shaft. It is provided with a pawl in the form of a bolt 39 pressed by a spring against the ratchet teeth 37 and having a head 40 by which it can be pulled up out of contact with these teeth. It is easy, therefore, to push this hub along the rack in one direction but it cannot be moved backwardly without raising the bolt 39. On this hub there is a friction roller 41 which is mounted to roll around on the surface of the table. The end of the shaft 36 is provided with a bevel gear 42 meshing with a bevel gear 43 keyed to the shaft 31.
- As the whole frame 32, 33, 34, 35 is pivoted on the axis of the shaft 31 the gears 42 and 43 will always be in mesh independently of the position of this frame. It is the rotation of the roller 41 caused by its travel around the table 22 that rotates the feed or

tension rolls 28 and 29 and controls the speed of delivery of the elastic thread E.

The parts are so proportioned that they always apply a tension to it and hold it back unless the roll 41 is located clear out at the end of the shaft 36 and the amount of drag is governed by the position of the roll along the shaft 36. It will be obvious that when the roll 41 is in its outermost position it will rotate at a maximum speed because the frame on which it is mounted rotates always at the same speed about the center of the knitting machine and the roll 41 has to make more revolutions on its own axis for every revolution of the frame about the center of the knitting machine if it is located at the circumference of the table 22. As it is moved in toward the center it makes fewer revolutions and consequently rotates the rolls more slowly. Therefore, these rolls will stretch the thread more between the rolls of the knitting machine and cause the resulting stocking to be contracted more when it leaves the needles.

The adjustment is secured manually by the operator by means of a screw 46 mounted in brackets 47 under the table and located radially. This screw has a handle 48 for operating it located conveniently at the circumference of the table. It also has a nut 49 which has extending up from it a bracket supporting a plate 50 which runs back and forth in a radial slot 51 in the table and constituting a part of the path for the roller 41 at all times. Extending up from the plate 50 is a support 52 carrying a horizontal slide 53 provided with a slanting tooth 54 on its end. This slide is pressed by a spring 57 so as to cause the tooth to engage the end of the hub 38 every time it comes around into contact with it. If the screw 46 has been turned a slight distance inward since the hub engaged the tooth 54 last, the contact of the hub with the tooth the next time will move the hub inwardly slightly. If it moves far enough to ratchet the pawl 39 over one of the teeth 37 it will be held against backward motion. A head 55 is provided on the slide 53 to draw it back whenever desired. It can be set by hand at any time but will be automatically adjusted always at the same point in the rotation of the wheel 41 around the circle.

In the operation of the device, the operator moves the wheel 41 and hub 38 along the shaft 36 until the wheel registers with the proper division on the scale 34 to produce a cylindrical stocking having the desired diameter. The machine is operated with the parts in that position as long as it is desired to produce a product of cylindrical form having a constant diameter. When it is desired to narrow it the operator turns the handle 48 a complete revolution

or any other number of revolutions or part of a revolution once during each rotation of the machine and sufficiently to cause the hub 38 to be advanced on its next engagement

5 with the tooth 54 the proper amount to secure the degree of narrowing which is required. This is worked out in advance and a card is provided for the operator showing her just how far and how often to 10 turn the handle. After all the narrowing is performed and the next stocking is to be produced, the member 40 is pulled up and the wheel 41 drawn back to its original position.

15 In this way the adjustment can be made to any desired degree of fineness and the operator has full control of the shape of the tubular product. There is no necessity of 20 making the product with zones of cylindrical portions separated from each other by sudden decreases in size but, on the contrary, the stocking can be tapered in a regular manner by the laying of each course so that the resulting product is smooth and 25 attractive as well as comfortable to wear. It is understood, of course, that ordinarily these products are made continuous, that is, a tube is formed having alternating enlargements and reductions and each stocking 30 is completed by cutting it from the continuous tube at the top and bottom and finishing the edges.

Although I have illustrated and described only a single form of the invention, I am 35 aware of the fact that modifications can be made therein by any person skilled in the art without departing from the scope of the invention as expressed in the claims. Therefore, I do not wish to be limited to all the

details of construction herein shown and described, or to the particular type of knitting machine illustrated, but what I do claim is:—

1. The combination with a knitting machine, of a table, a frame connected with said machine and rotatable by it over the table, a roller connected with said frame and resting on the table and adapted to roll around the table as the frame rotates, a shaft with which said roller is rotatable, 45 said shaft having ratchet teeth therealong, means on the roller for co-operating with said ratchet teeth to hold the roller against movement outwardly along the shaft, and manually adjustable means for engaging 50 the roller and pushing it inwardly along the shaft while it is rotating around the table.

2. The combination with a knitting machine, of a table, a frame connected with said machine and rotatable by it over the table, tension rolls carried by said frame, a roller also connected with said frame and resting on the table and adapted to roll around the table as the frame rotates, a shaft 60 with which said roller is rotatable, said shaft having ratchet teeth therealong, means on the roller for co-operating with said ratchet teeth to hold the roller against movement outwardly along the shaft, means operated by the shaft for rotating the tension rolls, 65 and manually adjustable means for engaging the roller and pushing it inwardly along the shaft while it is rotating around the table.

In testimony whereof I have hereunto 75 affixed my signature.

RICHARD M. FOSTER.
